[57] CLAIM

The ornamental design for a machine used for drilling, tapping and milling, and having an automatic tool changing system, as shown and described.

DESCRIPTION

FIG. 1 is a front elevational view of a machine used for drilling, tapping and milling, and having an automatic tool changing system showing my new design;

FIG. 2 is a rear elevational view thereof;

FIG. 3 is a left side end elevational view thereof;

FIG. 4 is a right side end elevational view thereof;

FIG. 5 is a top plan view thereof; and

FIG. 6 is a front, top and left side perspective view thereof.
